Harrison Gross, of Lititz, Penn.
Letters Patent No. 1168, dated Nov. 15, 1859.

The schedule referred to in these Letters Patent and making part of the same.

2

Res. 1/68

To all whom it may concern:

Be it Known, that I, Harrison Grosh, of Lititz, Warwick Township, County of Lancaster, State of Pennsylvania, invented a new and original design for carriage bodies and I do hereby declare that the following is a full and exact description thereof, reference being had to the accompanying drawings, and to the letters of reference marked thereon, making a part of this specification.

The nature of my invention consists in a grooved and round cornered seat.

A, represents the ordinary shape and construction of a carriage or Buggy Body.

B, represents a grooved seat with round corner to ornament and give a neater and more graceful appearance to the body.

This sweep is curved rounding at the corners and grooved and extends from the front of the Body upwards, and on both sides, and surrounds the top of the body at the top of the seat, so as to ornament the seat and top of the body, and is made of carved wood.

What I claim as my invention, and desire to secure by letters patent is, the design consisting of the grooved seat B, with the round corners to ornament the seat of a carriage or Buggy Body.

Witnesses.

J. Franklin Reigart, 3
